Primary Examiner — Calvin E Vansant*Assistant Examiner* — Eidiol Ghigliotti Torres(74) *Attorney, Agent, or Firm* — Thompson Coburn LLP(57) **CLAIM**

The ornamental design for a tent as shown and described.

DESCRIPTION

FIG. 1 is a left, front perspective view of a tent of my new design;

FIG. 2 is a front view thereof;

FIG. 3 is a rear view thereof (the left side view and right side view being identical thereto);

FIG. 4 is a top view thereof; and,

FIG. 5 is a bottom view thereof.

The dashed lines depict portions of the tent in which the design is embodied that are not considered part of the claimed design.
